(57) **CLAIM**

The ornamental design for a vehicle wheel, as shown and described.

DESCRIPTION

FIG. 1 is a perspective view of a vehicle wheel showing our new design;

FIG. 2 is a front elevational view thereof;

FIG. 3 is a right side elevational view thereof; the left side being a mirror image thereof; and,

FIG. 4 is a top plan view thereof; the bottom plan view being a mirror image thereof.

The rear of the vehicle wheel is unornamented and forms no part of the claimed design.
